CLAIM

The ornamental design for a multi-piece desk clock, as shown and described.

DESCRIPTION

FIG. 1 is a top, front and right side perspective view of a multi-piece desk clock showing my new design;

FIG. 2 is a front elevational view thereof;

FIG. 3 is a top plan view thereof;

FIG. 4 is a right side elevation thereof;

FIG. 5 is a left side elevation thereof;

FIG. 6 is a rear elevation thereof;

FIG. 7 is a bottom plan view thereof; and,

FIG. 8 is a perspective view of the multi-piece desk clock in an alternate arrangement with the pieces shown separated.

The broken lines shown in FIG. 8 are for illustrative purposes only and do not form part of the claimed design.
